UNITED STATES PATENT OFFICE.

MAX KRAUSS, OF PHILADELPHIA, PENNSYLVANIA, ASSIGNOR TO FRANKLIN E. BARR,
TRUSTEE, OF PHILADELPHIA, PENNSYLVANIA.

SOUND-BOX.

1,359,713.

Specification of Letters Patent. Patented Nov. 23, 1920.

Application filed April 17, 1920. Serial No. 374,542.

To all whom it may concern:

Be it known that I, MAX KRAUSS, a citizen of the United States, residing in the city and county of Philadelphia, State of Pennsylvania, have invented a new and useful Sound-Box, of which the following is a specification.

My invention relates in general to sound boxes for talking machines but is applicable with great advantage to boxes which comprise a dished or bulged diaphragm, that is to say a diaphragm having a concavo-convex form with the convexity facing outward.

15 The object of my invention is to employ a preferably but not necessarily dished diaphragm with a sound box of special and novel construction, the casing of which embodies, and may be said to be essentially composed of, a vibratory back made of mica or equivalent vibratory substance, so that between the inner face of the diaphragm and the fronting face of said back there exists a sound chamber, essentially and, so to speak, 20 entirely composed of vibratory material, within which the entering sound waves occasion the vibration not only of the diaphragm, but also of the back or rear face of the sound box itself, with the result that 25 the acoustic properties of the sound box as an entirety are greatly improved.

With the foregoing objects in view my invention comprehends a sound box of the character typically represented in the accompanying drawings and hereinafter described, the features which I claim as novel being definitely specified in the claims.

For the purpose of illustrating my invention, I have shown in the drawings two typical embodiments of it, which have given in practice novel and satisfactory results,— each of the said embodiments illustrating the same construction so far as its essential features are concerned, and the difference being 45 only in such mechanical features of assemblage of the operative elements as would be obvious to any skilled workman.

Referring to the drawings,

Figure 1 represents a front elevational view of a sound box embodying my invention;

Fig. 2 represents a transverse, sectional elevation of the sound box represented in Fig. 1, the dimensions, for clearer illus-

tration, being enlarged, and the section taken on line 2—2 of Fig. 1;

Fig. 3 represents in transverse, sectional detail a modified form of the separating ring represented in Fig. 2, removed from the sound box;

Fig. 4 similarly represents another modified form of said separating ring, likewise removed;

Fig. 5 represents a front, elevational view similar to that of Fig. 1 of a modified form of my sound box;

Fig. 6 represents an enlarged transverse, sectional elevation of the sound box represented in Fig. 5, the section being taken on line 6—6 of Fig. 5;

Fig. 7 represents, removed from the casing, a separating ring in the form of two knife-edged rings, which in their mounting as illustrated in Fig. 6, serve, when desired, to effect the dishing of the diaphragm.

Similar numerals of reference indicate corresponding parts.

Referring to the first four figures of the drawings:—

1 and 2 designate casing rings, between which are embraced the peripheral edges of a diaphragm 3, and also the peripheral edges of a back or rear face 4 of the sound box. The diaphragm, as usual, is composed of mica or equivalent vibratory substance, and the rear face of the sound box is also, as stated, composed of mica or similar substance.

A separating ring 5, illustrated in Fig. 2 as of diamond-shaped cross-section, which is of a diameter slightly less than that of the diaphragm and the back face of the sound box, is interposed between said diaphragm and said back face.

A plurality of fastenings such as the bolts 6 bear upon opposite faces of the casing rings 1 and 2, through apertures in which as shown in Fig. 2, they pass, and effect the clamping together of the diaphragm and of the back or rear face of the sound box, so as to effect the organization of a casing as a composite whole.

7 designates a casing or tone tube to which the back face of the sound box is attached and by means of which any usual or preferred connection with the tone arm of the talking machine is effected.

The connection or support of this tube 7

with relation to the back face of the sound box is conveniently through an outwardly extending flange 8 formed at the upper orifice of the tube, a plurality of fastening devices such as the bolts 9 and an annular washer 10, as shown in Fig. 2.

11 designates the operating arm or lever of the stylus, secured in any usual or preferred manner, as at 12, to the diaphragm.

10 13 is the rocking bar of the arm 11, which is susceptible of the usual vibratory or rocking movement by being mounted in bearings 14, of which any well known type may be used. 15 designates a stylus bar and socket, and 16 15 the stylus.

In Figs. 3 and 4 the separating ring instead of being diamond-shaped in cross-section, is elliptical,—in Fig. 3 the longer axis of the ellipse being vertical and in Fig. 4 20 horizontal.

The function of the separating ring being simply to peripherally separate the diaphragm and the vibratory back face of the sound box and form between them a sound 25 chamber, it is immaterial what its cross-sectional form may be, although it is preferable that it should have bearing or separating edges which are not flat.

It is also immaterial of what substance 30 the ring be formed, although I prefer to make it of metal.

In the modification represented in Figs. 5, 6 and 7, the peripheral edge of the vibratory back face 4 of the sound box, is encompassed by an inclosing wall 17, an internally extending flange 18 of which is beneath the periphery of said vibratory back face 4, and conveniently secured to it by a plurality of fastening screws 19 which also pass through 40 and secure a lower knife-edged ring 20.

A reversely formed upper knife-edged ring 21 of greater diameter than the lower ring 20, is conveniently superposed upon a rubber ring 22 the diameter of which is about 45 equal to that of the diaphragm, and is pressed upon the diaphragm and the ring 20 by a plurality of compressed springs 23 which serve to force down the peripheral edges of said diaphragm against the resistance of said lower knife-edged ring 20,—a rubber ring 24 being conveniently interposed between them,—with the result that by reason of the different diametric proportions of the two knife-edged rings any desired bulge 50 may be imparted to the diaphragm.

The springs 23 are conveniently held in place against the upper surface of the upper knife-edged ring 21, by a retaining ring 25 conveniently secured by screws 26 which 60 enter the wall 17.

Of course, in this construction in which a bulge of the diaphragm may be occasioned by the coaction of the knife-edged rings, such rings serve as a composite separating ring, so 65 to speak, and effect both the separation and

the inclosure of the diaphragm and back to form the desired sound chamber.

From the foregoing description it will be understood that the essence of my invention resides in a sound box the rear wall of which 70 is formed of mica or equivalent vibratory material and with which is combined by any preferred means of peripheral union, a diaphragm.

The union may be effected as in the construction of the first four figures, by a mere fastening together of the casing rings 1 and 2, with a simple separating ring between them,—or, as in the modified construction of Figs. 5, 6 and 7, the sound box may have an 80 inclosing wall 17, and the separation of the peripheries of its vibratory rear wall and of the diaphragm may be effected by the placing between them of the two knife-edged rings, the lower ring 20 subserving the dual 85 purpose of a separating and sound-chamber inclosing ring, as well as of a circular abutment with reference to which the upper knife-edged ring 21 acts upon the periphery of the diaphragm to effect its bulge. 90

The constructions so far as my invention broadly considered is concerned, are the same, because in each instance the rear face or back or wall of the sound box proper is composed of mica or equivalent vibratory material and the diaphragm of mica or equivalent vibratory material is so mounted with reference to the vibratory rear face of the casing as to effect the formation between them of a sound chamber within which the 100 pulsations of the sound waves take place and are increased or reduced in volume so as to reproduce vocal, musical and other tones of the desired pitch or character, which accurately correspond with the sound impulses emanating from the record which are to be reproduced. 105

The invention, as a matter of fact, comprehends a sound box essentially composed of two vibratory diaphragms, one being the 110 back or rear face or wall of the box proper, so to speak, and the other the ordinary disk or diaphragm proper to which the stylus lever is connected, the two diaphragms occupying and being connected in such spaced 115 relationship as to create between them a sound chamber.

Although, moreover, I have referred to the connection between the diaphragms as being peripheral, I do not desire to be understood as limiting it to the exact peripheries of the elements in the geometrical sense, but simply as being a connection,—preferably, but not necessarily, comprising separating means,—such as will give to the inclosed sound chamber a desirable diametric area, and a distance between the diaphragms sufficient to permit of an adequate vibration of both of them, which, of course, need not as to both of them be of equal extent. 120 125 130

The proportions, general dimensions, and outlines of the elements are also, of course, subject to variations, and the vibratory back may be either flat or dished toward or from 5 the diaphragm proper.

The thickness of the vibratory substance of which the back is composed may also be varied, having regard to both the necessary strength to secure the mounting of the box 10 as a whole upon the tone or casing tube, and the necessary vibratory quality.

Having thus described my invention, what I claim and desire to secure by Letters Patent, is:—

15 1. A sound box, the front and the rear walls of which are both composed of diaphragms connected near their peripheries so as to form between them a sound chamber,—a stylus operatively connected with 20 one of said diaphragms,—and a tone tube operatively connected with the other.

25 2. A sound box having its front wall formed by a vibratory diaphragm and its back wall also formed by a vibratory diaphragm,—means to connect said diaphragms in proximity to their peripheries,—a support between said diaphragms upon which they fulcrum,—a stylus operatively connected with the front diaphragm,—and a 30 supporting tone tube operatively connected with the back diaphragm.

3. A sound box formed by a front diaphragm and a rear diaphragm,—means for connecting said diaphragms near their pe-

ripheries,—a separating means radially internal of said connecting means, interposed between the diaphragms and upon which they fulcrum,—a stylus operatively connected with the front diaphragm,—and a tone tube operatively connected with the rear 40 diaphragm.

4. A sound box formed by a front diaphragm and a rear diaphragm,—means for connecting said diaphragms near their peripheries,—a separating means interposed 45 between the diaphragms upon which they fulcrum,—a stylus operatively connected with the front diaphragm,—and a tone tube operatively connected with the rear diaphragm.

5. A sound box which comprises a front diaphragm,—a stylus operatively connected with said front diaphragm,—a second diaphragm which constitutes the back of the sound box and which is peripherally connected with the front diaphragm so as to 50 form between them an inclosed sound chamber,—and a tone tube to an opening in which the back diaphragm is connected.

In testimony that I claim the foregoing as 60 my invention, I have hereunto this 14th day of April, 1920, signed my name.

MAX KRAUSS.
